UNITED STATES PATENT OFFICE.

ARLINGTON L. LEATART, OF LOS ANGELES, CALIFORNIA.

BIPLANE AEROPLANE.

1,197,505.

Specification of Letters Patent.

Patented Sept. 5, 1916.

Application filed May 2, 1910. Serial No. 558,881.

To all whom it may concern:

Be it known that I, ARLINGTON L. LEATART, a citizen of the United States, residing in the city of Los Angeles, county of Los Angeles, State of California, have invented new and useful Improvements in Biplane Aeroplanes, of which the following is a specification.

My invention relates to flying machines of the heavier than air type, and the object thereof is to construct a biplane-aeroplane having a maximum degree of stability which will be capable of being maintained in the atmosphere at any desired elevation, and which can be readily directed in any desired course.

In the accompanying drawings forming a part of this application, Figure 1 is a top plan view partly broken away of my improved machine. Fig. 2 is a side elevation of the same. Fig. 3 is a fragmentary enlarged front elevation with the front plane and steering apparatus removed for clearness of illustration. Fig. 4 is a rear end elevation showing the steering wings in a steering position in full lines, and in a soaring position in dotted lines. Fig. 5 is a front end fragmentary elevation of the main plane. Fig. 6 is the side elevation of the parts shown in Fig. 5. Fig. 7 is a fragmentary end elevation of the front and rear steering planes, and tail planes. Fig. 8 is a side elevation of the parts shown in Fig. 7. Fig. 9 is an enlarged detail of the steering post.

In the drawings the frame of the main plane 10 is formed of the front bar 11 and the upper rear bar 12 and lower rear bar 13. The upper bars are connected by longitudinal bars 14. At equal distances longitudinal upper ribs 15 are secured to the front bar 11 and to the upper rear bar 12, and project a short distance to the rear thereof. Intermediate the upper ribs are the lower ribs 16, which are also secured to the front bar 11 and to the lower rear bar 13. These ribs are covered with a fibrous covering such as silk or canvas. These ribs are bowed upwardly, the upper ribs having a greater curvature than the lower ribs, as best shown in Fig. 6, and with their covering form the main plane. Each portion which at its rear includes a triangle with the apex at the top I call a longitudinal section. Immediately below the main plane and of like construction is the breast plane 17, the outer ends

of which commence at a distance from the ends of the main plane and extend downwardly and inwardly to the center of the machine, as best shown in Figs. 2 and 3. 60 The upper ends of the breast plane are secured to the main plane wing bars, and the inner portions are secured to the body frame 18. Upon the bottom of the body frame are secured runners 19. Upon the 65 bottom end timbers 18^a are secured flat springs 21 by clips 22 which encircle the ends of the springs. A truck 23 is secured to the centers of these springs. The wheels 24 of this truck support the body when starting 70 and also when alighting if the machine comes down squarely on the ground.

Secured to the body frame and projecting therefrom is the tail frame 25, the top of which is covered by longitudinal sections 26 75 of a similar construction to the longitudinal sections of the upper main plane, except that the ribs thereof are straight and not bowed, and the rear portions end in the same vertical plane. To the bottom of the tail frame 80 are secured flat springs 27, by clips 28, which surround their front ends. These springs normally project at their free ends a short distance below the frame as best shown in Fig. 2, and carry a truck 29, which supports the rear end of the machine when on the ground. At the top and on each side of the tail frame are the triangular wing frames 30 which are in shape right angled triangles as best shown in Fig. 1. In these frames are 85 pivotally mounted at 31 and 32 the tail pieces 33. These tail pieces are also formed of longitudinal sections which are triangular in cross section at the rear end as best shown in Figs. 7 and 8. The rear rails 34 and 35 of these tail pieces are connected by vertical bars 36. To the lower inner corner of these wings are secured operating cables 37 and 38 which run over pulleys 39 and 40, which are mounted on the tops of the rear vertical timbers of the tail frame 41 and 42 and run thence to pulleys 43 and 44, and thence to the steering post 45 and are attached to the ends of the upper cross bar 45^b. These wings are also provided with cables 46 and 47, which are secured to the upper inner corners of these wings and pass downwardly over pulleys at the bottom of the tail frame, one of which pulleys 48 is shown in Fig. 2. They then pass forwardly over proper direction changing pulleys and are secured to the lower cross bar 45^a of the steering post. It 100 105 110

will be understood that when the steering post is rotated in one direction the inner corner on one side of these tail wings is elevated and the inner corner of the other wing is depressed as shown in full lines in Fig. 4. When the steering post is rotated in the reverse direction the movements of the inner corners of the wings are reversed. The steering post is revolubly mounted in a block 62, (see Fig. 9) which block is pivotally mounted in timbers 63 of the body frame so that the post can be oscillated as well as rotated. When the post is oscillated the corners of the tail wings are moved up or down in unison. To the wing bar 11 is secured a front wing frame 49 having a pointed front end as best shown in Fig. 1. The front portion of this frame is braced by timbers 50 which run to the body frame and are secured thereto. In this front frame are mounted the front steering wings 51. These wings are made up of longitudinal sections which are triangular in cross section at the rear end as the other longitudinal sections, but the ribs and the rear ends lie in the same vertical plane. There are two of these front wings and they are trapezoidal in shape, as best shown in Fig. 1. They are pivotally mounted in the front portion of the frame 52 and 53 so as to oscillate on their longer side. They are provided with wooden bars 54 running to a cross bar 45^b secured to the steering post so arranged that the rear ends of the wings can be either elevated or depressed at the will of the operator. The body frame carries the engine 56, which is preferably a gasolene engine of any approved type, and the propeller 57, which is driven thereby. The propeller is arranged to rotate at the rear of the body frame. The rear end of the outer lower ribs at each end of the main plane are preferably disconnected from the lower rear bar 13 and a cord 64 is attached to the free end of each of these ribs and runs over direction changing pulleys one of which 61 attached to bar 13, is shown in Fig. 3 and over other direction changing pulleys and are attached to bell crank foot levers 65 secured to the body frame. Normally in flight these outer lower ribs would be against the top bars as shown at the right in Fig. 3, but can be brought to the position shown in dotted lines by the aviator at any time he wishes. This would be desirable in case a gust of wind tipped the machine, or in case of turning by bringing either of these ribs to the position shown in dotted lines more resistance would be provided on that side, and equilibrium would be more quickly obtained by such change. It will be observed that in my construction the forward edges of all the wings and plane surfaces are straight lines and that the rear edges of all the wing and plane

surfaces, in vertical cross section area, are triangular. By this construction the front edge when in horizontal flight cuts through the air and the sides of the triangular rear portions gradually increase in depth and width which depresses a portion of the air passed through thereby lifting the machine, and at the same time gives an uneven pressure upon the air, and that the unevenness of pressure is the same in each longitudinal section which gives it greater transverse stability than if the surfaces were smooth. Another advantage of my construction lies in the fact that the rear ends of the longitudinal sections of the main plane and breast plane are, not only triangular in vertical cross sectional area, but terminate triangularly when viewed from the top, thereby allowing the air to escape out from beneath the sections on gradually increasing lines, instead of on a single line, thereby diminishing the tendency to eddy above the main plane. It will be observed that by my construction, and the peculiar way in which the tail pieces and front steering wings are mounted and operated that I have very great control over my machine, and that it can be easily steered in any direction, either up or down, or right or left. It will also be observed that I can quickly counteract the tendency of the machine to tip to either side, by throwing the tail piece on the lower side downwardly, and the front steering wing on the same side upwardly, and thereby bring the machine back to the horizontal plane. By connecting the breast plane to the main plane so as to form a triangle, greater stability is obtained as the upward slant of the breast plane, when either side of the machine tips, forms a pocket on the lower side which has a greater tendency to retard the further tipping to that side than straight surfaces would have. This effect is further heightened by the triangular shape of the surfaces. The parts of the frames are also properly braced by stay wires not numbered.

Having described my invention what I claim is:

1. In an aeroplane a main transverse plane having the front edge thereof a straight line and the rear edge of a plurality of angular lines, thereby forming a plurality of triangular shaped troughs opening downwardly.
2. In an aeroplane a main transverse plane and a V-shaped breast plane secured to the under side of the main plane intermediate the ends thereof, said breast plane having straight front edges and rear edges of a plurality of angular lines, thereby forming a plurality of triangular shaped troughs opening downwardly.
3. In an aeroplane a main transverse plane and a V-shaped breast plane secured to

the under side of the main plane intermediate the ends thereof, said planes having their front edges composed of straight lines and their rear edges of a plurality of angular lines, thereby forming a plurality of triangular shaped troughs opening downwardly.

4. An aeroplane comprising a transverse main plane, a V-shaped breast plane secured to the under side thereof intermediate its ends; a tail plane; tail pieces at the sides of the tail plane, all composed of longitudinal sections having straight front ends and angular rear ends, thereby forming a plurality of triangular shaped troughs opening downwardly; and front steering wings; and means to control the movement of the tail pieces and front steering wings.

5. In an aeroplane the combination of a main plane, a breast plane; a tail plane; tail pieces; front wings; with a steering post

operatively connected with said tail pieces and front wings, said steering post being mounted to oscillate and rotate.

6. In an aeroplane a main transverse plane having the front edge thereof a straight line and the rear edge of a plurality of angular lines, thereby forming a plurality of triangular shaped troughs opening downwardly, the outer troughs at each end of said transverse main plane being collapsible by virtue of the lower portion of said troughs being detached at their rear ends and said troughs being adjustable to their normal position.

In witness that I claim the foregoing I have hereunto subscribed my name this 22nd day of April, 1910.

ARLINGTON L. LEATART.
